(57) **CLAIM**

The ornamental design for a brush head for electric toothbrush, as shown and described.

DESCRIPTION

FIG. 1 is a perspective view of a brush head for electric toothbrush showing our new design.

FIG. 2 is a front elevational view of our brush head.

FIG. 3 is a rear elevational view thereof.

FIG. 4 is a left side elevational view thereof.

FIG. 5 is a right side elevational view thereof.

FIG. 6 is an enlarged top plan view thereof; and,

FIG. 7 is an enlarged bottom plan view thereof.

The broken lines illustrate portions of the brush head for electric toothbrush that form no part of the claimed design.
